SHIPPING CARTON FOR BOTTLES

Albert A. Mayer, Little Falls, N. J., assignor to
 John F. Trommer, Inc., Brooklyn, N. Y., a corporation of New York

Application February 20, 1945, Serial No. 578,854

1 Claim. (Cl. 229—15)

1

This invention relates to cartons and more particularly to shipping cartons for bottles.

The object of the invention is to provide a carton adapted to hold bottles for beverages, which carton may be readily closed and opened, and which, when closed, will serve to hold the bottles in compartments, or in spaced relationship secure against breakage.

The invention consists in the interlocking of certain of the flaps of a carton with slots in certain of the other flaps, the flaps inserted through said slots entering the interior of the carton and acting to separate certain of the bottles. The invention provides in addition a compartment forming partition for forming compartments in the interior of the carton and disposed adjacent the inserted flaps and cooperating therewith.

The invention will be more fully described hereinafter, embodiments shown in the drawings, and the invention will be finally pointed out in the claim.

In the accompanying drawings,

Fig. 1 is a prospective view of an embodiment of the invention with parts broken away;

Fig. 2 is a section taken on line 2—2 of Fig. 1;

Fig. 3 is a section taken on line 3—3 of Fig. 2;

Fig. 4 is a plan view, showing the lids open;

Fig. 5 is a section of a modified construction;

Fig. 6 is a perspective view of the separating partition;

Fig. 7 is a longitudinal section of a modified construction;

Fig. 8 is a fragmentary top view, and

Fig. 9 shows a plurality of cartons disposed in a container.

Similar characters of reference indicate corresponding parts throughout the various views.

Referring to the drawings, the carton 10 for eight bottles, as shown in Figure 1, is inserted into a container 11, with the cover flaps of the carton bent down (Fig. 9), and three of such cartons are grouped in the container 11, and then the lids 12 of the container are closed. This provides a container for shipping twenty-four bottles. With the cartons empty and the lids of the container open, the cartons can be readily filled by a bottle filling machine of the bottle maker, which machine fills the empty bottles into place. The beer bottler or brewer when he receives the container takes out the empties, fills them, and after passing them through the labelling machine, loads the cartons by means of a bottle filling machine. The cartons with the top flaps bent back are then placed into the container, and the lids of the container are closed. The container

2

is then delivered to the retailer, who opens the lids and finds the tops of the cartons flush with the top of the container. When a customer purchases a carton of bottles, the retailer may first exhibit the bottles and their labels, and then extracts a carton from the container, closes the flaps thereof, and hands the closed carton to the customer.

Referring to Figures 1 to 5, each carton consists of the usual four upright walls 13. Two opposed walls have opposed top and bottom flaps 14, each with a slot 15, and the two other opposed walls have additional flaps 16.

When the bottom flaps 14 with their slots 15 have been moved to their closed position, the bottom flaps with their flaps 16 are then moved to closing portion by passing the flaps 16 through the slots 15, until the adjacent flaps 16 are parallel with each other and protrude into the inside 20 of the container. These parallel and upright flaps 16 then form a partition extending longitudinally of the carton and separate the bottles when in the carton, four on each side of the partition formed by the flaps 16.

Upon these flaps 16 is placed a bottle separating partition 17. This consists of one piece, bent into shape to form transverse barriers 18 between each transverse pair of bottles, the intervening webs 19 being arranged parallel with the inner 30 side of the longitudinal wall 13 of the carton. The height of the partition is equal to the distance between the top edge of the lower flaps 16, and lower edge of the upper flaps 16, when the latter are inserted. These upper flaps 16 are passed through the slots 15 of the upper flaps 14, and inserted into the inside of the container and then rest on, or contact with, the upper edges of the partition 17. This partition 17 may be of any other suitable construction, but is held in position by the flaps 16 when these are inserted.

The essential feature is the provision of means in one pair of flaps to permit the entrance therethrough and holding thereby the additional flaps 16 of another pair of flaps to provide a convenient 45 closure for a carton, and to act as a bottle separator for the bottles filled in the carton.

A modified form of construction of the bottle partition provides the extension of the partition 17 to the full height of the interior of the carton. In this form, the partition 17 is provided with slots 20 to be engaged by the flaps 16 when inserted, as shown in Figs. 5 and 6. In another form of construction the partition 17 is left unslotted and the flaps 16 are provided with slots 21, 55 which are engaged by the flaps 16 when inserted,

as shown in Figs. 7 and 8. In these figures, the flaps 14 have slots for the passage of the flaps 16.

Instead of two transverse, and four longitudinal bottles, other dispositions can be made.

In the embodiments shown, the height of the interior of the cartons is about the height of the bottles, in order that the top and bottom flaps hold the bottles at their tops and bottoms. The inserted additional flaps separate the bottles by acting as a wall in one direction of the carton contacting with the lower portions of the bottles. The partitions separate the bottles transversely. The cooperation of this wall and the partitions transversely thereto thereby serve to form one compartment for each bottle, in a manner preventing the bottles knocking against each other. The provision of one pair of opposite flaps of each carton with slots and the other pair of opposite flaps with additional bent over flaps to enter the slots, results in a quick closing and opening of a carton without the use of paste, or gummed strips or tying strings. Furthermore, a carton is provided which can be filled with empties at the bottle factory by a bottle filling machine, and the same carton can be filled with beverage filled bottles by bottle filling machinery at the brewery or bottling plant, the beverage filled bottles reaching the customers without the cartons being emptied.

I have described several forms of my invention, but obviously various changes may be made in the details disclosed without departing from the spirit of the invention as set out in the following claim.

I claim:

30 A shipping container for bottles having a closed

body portion forming an open top and bottom, and closing flaps each hinged to the top and bottom edges of each sidewall for closing the open top and bottom, the combination of an additional flap on each one of a pair of opposed flaps, each of a depth to extend vertically into the container sufficiently to form with its adjacent additional flap, a separator for the bottles, one at the top and one at the bottom, and a plurality of vertical partitions transverse to said separators and engaging said separators, the other pair of opposed flaps, each having a slot extending from the edge of the flap to its bottom near the hinge of the flap, the slots of the two opposed flaps being aligned and each having a width of substantially the two additional flaps, the distance between the bottoms of the aligned slots being equal to the length of the additional flap, the top and bottom flaps forming a closure for the container with the additional flaps and partitions forming compartments of the bottles, one separated from the other.

ALBERT A. MAYER.
